CLAIM

The ornamental design for a steam pot, as shown and described.

DESCRIPTION

FIG. 1 is a front and top perspective view of a steam pot, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof; and,

FIG. 9 is an enlarged perspective view of detail "9" identified in FIG. 1.

The dashed lines in the figures illustrate portions of the steam pot that form no part of the claimed design. The dash dot, dash lines in FIGS. 1 and 9 are for the purpose of depicting the boundary lines of the enlarged view and form no part of the claimed design.

1 Claim, 9 Drawing Sheets
